UNITED STATES PATENT OFFICE.

DANIEL L. OULTON, OF EVERETT, MASSACHUSETTS, ASSIGNOR TO OULTON MANUFACTURING CORPORATION, A CORPORATION OF VERMONT.

PNEUMATICALLY-ACTUATED TOOL.

Application filed October 6, 1924. Serial No. 741,784.

My invention relates to that type of apparatus wherein a reciprocating part is designed automatically to actuate, or strike repeated blows upon, a drilling, cutting, hammering or chopping tool, said reciprocating part being actuated by pneumatic pressure. It has been the special object of my invention to produce a simple and easily operated device which shall exhaust the air under the compression as soon as its work has been performed and take in a fresh supply of air to be compressed thereby preventing the undue heating of the device which would otherwise be occasioned by the maintenance within the system of a nearly unchanging body of air, as in the so-called "pulsating" type of pneumatically actuated tool.

My invention consists, further and finally, in the feature combinations and details of construction hereinafter described and claimed.

My device may be best understood by reference to the accompanying drawings in which

Fig. 1 is a side view, largely in section, of the air compressor.

Fig. 2 shows in longitudinal cross-section the tool-cylinder.

Fig. 3 shows in cross-section an enlarged detail view of the trigger-valve in the tool-cylinder.

Fig. 4 is a cross-section on line 4—4 of Fig. 1.

Fig. 5 shows the construction and arrangement of the metallic and fabric packing rings in the stuffing box of the air compressor.

Fig. 6 is a sectional front view of the air compressor.

Fig. 7 is a sectional view on line 7—7 of Fig. 6.

Fig. 8 is a cross-section of the oil pump.

Fig. 9 is a cross-section on line 9—9 of Fig. 2.

Fig. 10 is a cross-section on line 10—10 of Fig. 2.

Referring now more specifically to the drawings, 1 is the base-casing of the air compressor within which is the crank-shaft 2 which carries a fly-wheel 3. The crank-shaft 2 actuates the crank 4 which is connected by the wrist-pin 5 with the sleeve 6 which is slidably mounted within a small cyl-

inder 7 which projects upward within the base of the compressor cylinder 8 (see Fig. 6).

Mounted on a transverse web 9 within the sleeve 6 is a piston rod 10 which passes through a stuffing-box 11 mounted in the top of the small cylinder 7. The stuffing-box 11 is packed with alternate rings 11^a of cast iron and canvas, 11^b, the iron rings 11^a being split, as shown in Fig. 5, so that they may be sprung closely about the piston-rod 10. The piston-rod 10 bears the piston 12 which has a close sliding fit within the cylinder 8.

The crank-shaft 2 has fast thereon a gear 13 which meshes with a gear 14 fast on the end of a drive shaft 15 which may be actuated by a motor or other convenient source of power.

Fast on the shaft 2 is another gear 16 which meshes with an intermediate gear 17 on shaft 18 mounted in base 1. The gear 18 meshes with and actuates a gear 19 fast on shaft 20 mounted on a bracket 21 which is attached by screws 22 to the base 1. The shaft 20 is provided with a fly-wheel 23 which bears an off-set crank pin 24 on which is mounted the crank 25. The crank 25 is attached by means of a wrist-pin 26 to the slide-valve 27 which is arranged to slide over the flattened outer surface of the adjacent exterior of the cylinder 8 which is provided with integral lateral guide ways 28 and 29.

Ports 30 and 31 in the side of the compressor cylinder 8 are located respectively above and below the piston 12 near the end of its stroke. The slide valve 27 is also provided with a port 32. Screwed to the guide-ways 28 and 29 is an air-strainer casing 33, the back of which forms a support for the slide-valve 27 although it is provided with a large opening 34 through which air may pass to ports 30 and 31. The open front of the casing 33 is covered by three sheets of fine wire gauze 35 forming an air-strainer. (See Fig. 6.)

The compressor cylinder 8 is provided with outlet ports 36 and 37 into which screw nipples 38 and 39 to which are attached respectively hoses 40 and 41. Between the outlet ports 36 and 37 is an opening 42 provided

- with an annular lip 43. A plug 44, a portion of which has a threaded surface, screws into this opening 42 and may be seated against the annular lip 43. (See Fig. 4.)
- 5 A passage 45 leading from said opening 42 communicates with the interior of the air-strainer-casing 33. Adjacent to the passage 45 the opening 42 is enlarged so as to permit air to pass around the plug 44.
- 10 Fixed to the side of the base-casing 1 is an oil pump-casing 46, (see Fig. 8), having a cylindrical bore 47 into which fits closely the plunger 48. A coil-spring 49, surrounding the plunger 48 and contacting at one end 15 with the top of the pump-casing 46 and at the other end with an annular lug 50, serves to keep the plunger 48 normally in an elevated position. The plunger 48 is thrust downward by the contact of a lug 51 on the sliding valve-plate 27. An oil strainer-casing 52 has a pipe extension 53 which screws into the bore 47 of the pump-casing 46. This pipe extension 53 is so cupped at its top 20 as to form a seat for a ball-valve 54 above which is located a stop-pin 55. Across the open bottom of the oil strainer-casing are mounted three sheets of fine wire gauge 56 forming an oil-strainer. An oil outlet passage 57 leads from the pump bore 47 above 25 the ball-valve 54. This passage 57 is also provided with a cupped seat 58 wherein normally rests a ball valve 59 above which is a stop-pin 60. The top of the passage 57 is threaded at 61 to receive the threaded end 30 of an oil pipe (not shown) by which the oil may be suitably distributed to various moving parts to be lubricated.
- The tool cylinder 63 has a bore 64 within 35 which is a floating piston, or hammer, 65.
- 40 A port 66 communicates with the top of said cylinder bore 64 and into this port is screwed a nipple 67 to which is attached the hose 40. There is formed in the side of the tool-cylinder 63 a passage 68 into which is screwed a nipple 69 to which is attached the hose 41. The passage 68 communicates with the base 45 of the cylinder bore 64. A passage 70, leading to the outer atmosphere, communicates with the cylinder bore 64 at a point slightly 50 above the top of the floating piston, or hammer, 65 when it is in contact with the tool 71 which is mounted with close sliding fit in a cylindrical hole in the end of the tool-piston 63. The tool 71 has a shoulder 72 which 55 limits the extent of its entrance into the tool-cylinder 63 but the entering part thereof extends slightly above the base of the cylinder bore 64 and is surrounded by a short stiff coil-spring 73.
- 60 The tool-cylinder 63 is provided with a handle 74 through the forward part of which passes the stem 75 of a trigger-valve 76. Surrounding the stem 75 is a coil-spring 77, one end of which engages the back 65 of the valve 76 while the other end rests in the bottom of a pocket 78 in the back of tool-cylinder 64. A port 79 leads from the pocket 78 to the outer atmosphere. The normal action of the coil-spring 77 is such as to thrust the valve 76 outward from the pocket 78 until it enters and closes the bore 64 of the tool-cylinder 63. The valve 76 may, however, be retired till it becomes seated on the outer rim of the pocket 78 thereby closing the pocket 78. To effect such retirement of the valve 76 a trigger 80 is provided. This trigger 80 is attached at one end by the pivot 81 to the handle 74 and at the other end it is attached to the end of the valve stem 75. The back of the handle 74 is slotted at 82 to 80 receive the trigger 80 when it is pressed into its position of extreme retirement as shown in Fig. 2.
- The operation of my device is as follows: The application of rotative power to the 85 shaft 15 will, through the gears 14 and 13 rotate the shaft 2 thereby reciprocating the crank 4 and the piston 12. At the same time the shaft 20 is rotated by the gears 16, 17 and 18 thereby reciprocating the crank 25 90 and the attached valve plate 27. The gears 16, 17 and 18 are so set and timed that as the piston 12 starts upward from its lowest position, as shown in Fig. 6, the port 30 will be speedily closed by the valve plate 27 and the 95 port 31 will be opened. The reverse action occurs when the piston 12 starts downward from its position of extreme elevation; the port 30 is opened and the port 31 is closed. This cycle of operations causes air alternately to be compressed in the cylinder 8 in the chambers above and below the piston 12, and expelled through the pipes 40 and 41. Following the compression strokes, air is drawn in through ports 30 and 31 by the return or suction strokes. It is to be observed 105 that the air always passes out through the pipes 40 and 41 and in through the ports 30 and 31.
- When the trigger 80 is pressed back so as 110 to retire the valve 76 to the position shown in Fig. 2 the impulse of the air projected through pipe 40 by the upward movement of the piston 12 will force the floating piston, or hammer, 65 downward against the tool 71 115 in which position the compressed air is exhausted through the passage 70, whereupon succeeding downward movement of the piston 12 will produce an impulse of air through the pipe 41 and passage 68 thereby 120 forcing the hammer 65 again into elevated position temporarily closing the passage 70 until the hammer nears its extreme position of elevation when the compressed air beneath the hammer likewise is exhausted through the passage 70. The exhaust through the passage 70 is thus nearly continuous and may be utilized as a blower to blow dust away from the cutting tool 71. As there is no suction into the passage 70 the 130

dust of the tool is never drawn into the tool cylinder so as to become a destructive agent. The spring 73 serves to assist the recoil of the hammer 65, upon its impact with the 5 tool 71, so as to permit the compressed air to exert its influence to further elevate it.

When the trigger 80 is in normal position the valve 76 is in the position illustrated in Fig. 3, closing the top of the tool cylinder 10 63 to the entrance of air from the pipe 40. Pressure impulses coming from pipe 40 are exhausted through the port 79, while those coming from pipe 41 are exhausted through the passage 70, the hammer 65 remaining at 15 rest near the top of the chamber 64.

The force of the impulses of air through pipes 40 and 41, and consequently the power of the hammer 65, may be diminished in varying degree by turning the plug so as to 20 back it more or less off its seat 43, (see Fig. 4), thereby permitting some of the air under pressure, alternately on each side of piston 12, to escape through the passage 45.

The plunger 48 of the oil pump is reciprocated by the downward thrust of the lug 51 on the reciprocating valve plate 27, and the upward thrust of the spring 49. Upon the upward thrust of the plunger 48 the ball-valve 54 lifts and admits oil to the pump-bore 47 whence it is expelled, by the downward thrust of the plunger, into the passage 57.

The ball-valve 59 lifts automatically to permit the outward flow of oil and seats automatically on the suction stroke of the 35 plunger 48.

My device possesses the great merit of keeping always cool, no matter what the speed of operation may be, because no constant pressures are maintained anywhere in 40 the system and there is a constant passage through the system of freshly intaken, cool atmospheric air. Because of this, and because of its flexibility, and simplicity it can safely be operated at high speed.

45 Having thus fully described my invention what I claim is:—

1. In a device of the character specified the combination of a tool-cylinder provided with an exhaust port located intermediate the 50 ends thereof, a tool-piston in said tool-cylinder adapted to close said exhaust port during a part of its movement, an air-compressor, a passage connecting said air compressor with the front of said tool-cylinder, and a 55 second passage connecting said air compressor with the rear of said tool-cylinder, said passages being at all times free and unobstructed while said device is in operation and said air-compressor being provided with 60 two compression chambers each of which connects with one of said passages and each of which is provided with a valve adapted to be opened upon the suction stroke of a compressor piston and closed upon the pressure stroke thereof, said exhaust port in said 65

tool-cylinder being of size sufficient to fully and freely exhaust the force of compression existing in said tool-cylinder when said exhaust port is not closed by said tool-piston.

2. In a device of the character specified 70 the combination of a tool-cylinder provided with an exhaust port located intermediate the ends thereof, a tool-piston in said tool-cylinder adapted to close said exhaust passage during a part of its movement, a compressor-cylinder, a compressor-piston in said compressor-cylinder, outlet ports in said compressor-cylinder, there being an outlet port 75 on each side of said compressor-piston, a passage from the front of said compressor-cylinder to the rear of said tool-cylinder and a passage from the rear of said compressor-cylinder to the front of said tool-cylinder, said passages being at all times free and unobstructed while said device is in operation, 80 intake ports in said compressor-cylinder, there being an intake port on each side of said compressor-piston, valves arranged to control said ports, said valves being adapted 85 to close at the start of the compression stroke thereof and open at the start of the suction stroke of said piston, said exhaust-port being of size sufficient to fully and freely exhaust the force of compression existing in said tool-cylinder when said exhaust-port is not 90 closed by said tool-piston.

3. In a device of the character specified the combination of a tool-cylinder provided with an exhaust port located intermediate the 100 ends thereof, a tool-piston in said tool-cylinder adapted to close said exhaust passage during a part of its movement, a compressor-cylinder, a compressor-piston in said compressor-cylinder, outlet ports in said compressor-cylinder, there being an outlet port 105 on each side of said compressor-piston, a passage from the front of said compressor-cylinder to the rear of said tool-cylinder and a passage from the rear of said compressor-cylinder to the front of said tool-cylinder, said passages being at all times free 110 and unobstructed while said device is in operation, intake ports in said compressor-cylinder, there being an intake port on each side of said compressor-piston, valves arranged to control said ports, said valves being adapted 115 to close at the start of the compression stroke thereof and open at the start of the suction stroke of said piston, said exhaust-port being of size sufficient to fully and freely exhaust the force of compression existing in said tool-cylinder when said exhaust-port is not closed by said tool-piston, a compression relief port in said compressor-cylinder, 120 means for closing said compression relief port, and means whereby said closure means may be opened to a varying degree.

In witness whereof I have hereunto affixed my signature.

DANIEL L. OULTON.
